UNITED STATES PATENT OFFICE.

HILDOR FREDRIKSSON, OF CHICAGO, ILLINOIS, ASSIGNOR OF ONE-HALF TO CARL BLOOMBERG, OF CHICAGO, ILLINOIS.

CARBURETER ATTACHMENT.

1,302,534.

Specification of Letters Patent.

Patented May 6, 1919.

Application filed April 23, 1917. Serial No. 163,820.

To all whom it may concern:

Be it known that I, HILDOR FREDRIKSSON, a citizen of the United States, and a resident of Chicago, in the county of Cook and State 5 of Illinois, have invented certain new and useful Improvements in Carbureter Attachments, of which the following is a specification.

This invention relates to carbureter attachments and is designed to coöperate with the air intake of a carbureter, for the purpose of automatically regulating the amount of air supplied to the carbureter in direct proportion to the speed of the engine or the 15 amount of gasoline fed to said engine.

With the above and other objects in view, as will be apparent, this invention consists of the construction, combination and arrangement of parts, all as hereinafter more 20 fully described, claimed and illustrated in the accompanying drawing, wherein:—

Figure 1 is a side elevation of the air intake of a carbureter, the exhaust pipe of the engine and the carbureter being fragmentarily illustrated, while the present invention is illustrated in dotted lines.

Fig. 2 is a vertical section taken along line 2—2 of Fig. 1.

Fig. 3 is a central vertical section taken 30 along line 3—3 of Fig. 2.

Fig. 4 is a horizontal section taken along line 4—4 of Fig. 1 to illustrate the relative positions occupied by the air intake pipe and the engine exhaust pipe; and

Fig. 5 is a bottom plan view of the present attachment.

In practice, as the speed of an internal combustion engine is increased, so must the amount of gasoline supplied to the engine 40 be increased, and unless the mixture is maintained by increasing the air therein, the fuel or gas delivered to the engine will be rich in gasoline, thereby increasing the cost of operation as well as decreasing the efficiency of the engine. Likewise, as the speed of the engine is increased, the suction through the carbureter is increased. The present invention is primarily designed to provide an automatic control without the 45 use of springs and other easily broken mechanisms which will control the air supply admitted into the carbureter in direct proportion to the degree of vacuum in the engine, which is, of course, directly depend-

ent upon the speed of the engine, and hence, 55 upon the gasoline supply.

Reference being had more particularly to the drawings, C represents the air intake of the carbureter, while E designates the exhaust pipe of the internal combustion engine. An air supply pipe 10 extends from the exhaust pipe E, which is superposed above the carbureter C and terminates at its lower end in the intake bushing 11 of said carbureter. At its upper end, to wit, that 60 end removed from the terminal coöoperating with the bushing 11, the air supply pipe 10 is flared as at 12 to embrace the engine exhaust pipe E in order that the air taken into the pipe 10 may be withdrawn from 65 around the pipe E so that it is partially heated thereby. The lower end of the air supply pipe 10 is curved as at 13 to create the horizontal portion 14 thereof, which enters the carbureter bushing 11 as indicated. 75

The present invention is approximately located in the horizontal portion 14 of the pipe 10 and comprises a cylinder 15 which is inserted in the terminal of the horizontal portion 14 of the pipe 10. This cylinder 80 may be tapered for the purpose of facilitating the insertion thereof into the horizontal portion, and is so located within said horizontal portion that its terminal lies in substantially the same plane as the terminal 85 of the horizontal portion, as indicated in Fig. 3 of the drawing. The upper section of the wall of the cylinder 15, when the same is properly positioned in the horizontal portion 14, is bent inwardly to create the oblique 90 arranged flange 16 formed from the body of the cylinder. The lower portion of the wall of the cylinder 15, when the same is properly positioned in the horizontal portion 14 of the pipe 10, is triangularly 95 bifurcated as at 17 to create the two somewhat triangularly formed lips 18 in order that the present attachment may accommodate the curve 13 in the pipe 10.

The lower edge of the flange 16 terminates 100 adjacent a hinge pin 19 arranged transversely of the cylinder 15 parallel to the free edge of the flange 16, to which is pivoted the gate valve 20 which freely swings upon a horizontal pivot, as illustrated in 105 Fig. 3. The surface of this gate valve removed from the lips 18, has a weight 21 fixed thereto, which acts upon the gate valve

20 to normally maintain it in a vertical position, the normal position of said valve being illustrated in Fig. 3. By triangularly bifurcating the inner end of the cylinder 15, 5 as at 17, thereby creating the lips 18, the curve 13 of the air supply pipe 10 is accommodated so that no jamming will occur between the cylinder 15 and the curved portion 13 of the supply pipe 10 when the 10 former is inserted into the horizontal portion 14 of said pipe. As the speed of the engine with which the present invention cooperates increases, the suction through the air supply pipe 10, and consequently 15 through the cylinder 15 in the direction of the arrow in Fig. 1, is increased, thereby lifting the gate valve in the direction of the arrow in Fig. 3 a distance directly proportionate to the suction created. When the 20 engine reaches its maximum speed, the valve 21 will assume an approximately horizontal position, but as the speed of the engine decreases, and the suction likewise decreases, the weight 21 of the valve 20 will cause it 25 to gradually assume a vertical position, until the engine ceases operation, when it will assume the position illustrated in Fig. 3. Thus, as the amount of fuel supplied to the 30 carbureter is increased, in order to increase the speed of the engine, the amount of air admitted into the carbureter is likewise increased automatically and without manual assistance. This is responsible for a great 35 saving in gasolene, it being possible to greatly increase the mileage per gallon.

From the foregoing, it becomes manifest that the formation and position of the air supply pipe 10 is immaterial to the opera-

tion and function of the present invention, the latter being equally applicable to all 40 types of air supply pipes and all types of carbureters, the only changes which may be necessary being in the size, proportions and details of construction. Furthermore, the weighted gate valve 20 may be built into 45 either the air supply pipe or the carbureter.

What is claimed is:

1. The combination with a cylinder, of an obliquely arranged flange formed therefrom, a gate valve pivoted adjacent to said flange, and lips projecting beyond said gate valve created by triangularly bifurcating said cylinder. 50
2. The combination with a tapered cylinder, of an inwardly extending flange formed therefrom, a freely swinging gate valve pivoted adjacent to said flange normally occupying that portion of the cylinder not occupied by said flange, and lips flanking said valve and extending beyond the same, created by triangularly bifurcating one end of said cylinder. 55
3. The combination with a tapered cylinder, of an inwardly extending obliquely arranged flange formed therefrom, a freely swinging gate valve pivoted adjacent to the edge of said flange, normally occupying that portion of the cylinder not occupied by said flange, and lips flanking said valve and extending beyond the same created by bifurcating one end of said cylinder so that the bifurcated end of the cylinder is curved upon 60 one side and obliquely arranged upon the other side. 70

HILDOR FREDRIKSSON.
